MAGAZINE GUN

Robert Schultz, New Liepzig, N. Dak.

Application May 25, 1935, Serial No. 23,500

18 Claims. (Cl. 42—17)

This invention relates to guns and particularly to magazine guns.

The general object is to provide improved means whereby the cartridges contained in a magazine may be shifted one by one into firing position from the magazine into the breech of the gun, the magazine being so constructed as to contain a large number of cartridges by providing means whereby the cartridges may be supported in the magazine in a position which is nearly vertical instead of a longitudinally aligned position.

A further object is to provide a gun of this character with a magazine which may be readily removed, loaded, and re-inserted in the gun.

A further object is to provide a mechanism of this character which is so constructed that upon the rearward movement of the breech block a cartridge will be withdrawn from the magazine, carried upward, discharging the spent cartridge and carried into position immediately in alignment with the barrel, and upon a closing movement of the breech block, the cartridges within the magazine will be given a one step movement toward the breech block.

A still further object in this connection is to provide a ratchet bar for moving the cartridges, which is moved rearward upon the opening movement of the breech block and is shifted forward upon the closing movement of the breech block to thus act to feed the cartridges in the magazine toward the breech block.

Other objects will appear in the course of the following description.

My invention is illustrated in the accompanying drawings wherein:

Figure 1 is a longitudinal sectional view through the frame and breech portion of my magazine gun, the parts being shown in the position which they occupy when the cartridges are being fired;

Figure 1^a is a sectional view through the barrel and stock of the gun shown in Figure 1;

Figure 2 is a fragmentary section on the same line as Figure 1, showing the parts in the position taken when the breech block is partially retracted;

Figure 3 is a like view to Figure 2 but showing the parts in the position taken by them when the breech block is fully retracted to carry a new cartridge into position in alignment with the barrel and to eject the spent cartridge;

Figure 4 is a longitudinal section through the fore-stock and frame of the gun showing the exterior of the magazine and breech block in eleva-

tion but with the covering plate for the magazine removed;

Figure 4^a is a like view to Figure 4 but showing that portion of the cartridge feeding mechanism toward the forward extremity of the fore-stock; 5

Figure 5 is a top plan view of the breech or firing chamber of the gun with the breech block removed;

Figure 6 is an under side plan view of the breech block; 10

Figure 7 is a front elevation of the breech block;

Figure 7^a is a rear elevation of the breech block, the housing being in section;

Figure 8 is a section through the breech housing and breech block on the line 8—8 of Figure 1; 15

Figure 9 is a side elevation of the magazine detached from the gun;

Figure 10 is a fragmentary elevation of the magazine shown in Figure 9, but with the cartridge feeding cam in a retracted position taken when the magazine is being withdrawn; 20

Figure 11 is a fragmentary elevation of a portion of the magazine showing the feeding plate lifted; 25

Figure 12 is a section on the line 12—12 of Figure 4;

Figure 13 is an enlarged vertical section through the magazine with the follower removed; 30

Figure 14 is a fragmentary elevation of a breech housing showing the stock or the finger piece of the breech block; 35

Figure 15 is a fragmentary longitudinal sectional view through the breech block to show the cartridge clamping jaws. 35

Figure 16 is a perspective view of the follower.

Referring now particularly to Figures 1 and 2, the frame of the gun is designated 10, the fore-stock 11 and the barrel 12, the breech housing being designated 13. Disposed within the breech housing is the hammer 14 pivoted at 15 and urged forward by the usual spring 16. The hammer is held in its retracted position by a sear 17 capable of being released by a trigger 18, the nose 19 of this trigger operating upon a block 20 urged downward by a spring 21. When the hammer is retracted, as shown in Figures 2 and 3, the sear engages a notch 22 in the hammer and holds the hammer in retracted position. When the trigger is pulled, the block 20 lifts against the action of spring 21 and the hammer is released and thrown forward against the firing pin by the springs 16. This trigger mechanism may be of any usual or suitable construction. 40

The firing pin 23 at its rear end is cylindrical, 55

as at 24, and fits within a bore 25 in the breech block 26. The under face of the firing pin is cut away at 27 to provide a slot and a stop pin 28 acts to limit the movement of the firing pin. 5 The forward end portion of the firing pin is longitudinally recessed at 29, and operating within this recess is a plunger 30 urged forward so that its nose is slightly beyond the firing pin when the latter is in a retracted position by means of 10 the spring 31. This plunger 30 acts to hold the cartridge and to press the cartridge firmly into the barrel by bearing against the flanged rim of the cartridge and when the hammer strikes the rear end portion 24 of the firing pin, it drives 15 it forward into the rim of the cartridge, thereby detonating the cartridge. When the hammer is retracted to the position shown in Figure 2 by the retraction of the breech block 26, the firing pin will be pushed rearward by the spring 20 31.

The breech block 26 is provided with the laterally projecting knurled handle 32, as shown in Figures 6 and 7 and is urged forward to the position shown in Figure 1 by the springs 33 surrounding the guide pins 34, these pins having heads 35 at their rear ends bearing against the rear wall of the breech block chamber, the forward ends of these pins and springs entering bores formed in the breech block as usual, and 30 shown in Figure 7^a. The breech block 26 is shown in Figures 6, 7, 7^a and 8, and is provided in its side walls with longitudinally extending grooves 36 in the forward ends of which are disposed the latches 37, as shown in Figure 15, the 35 forward end of each latch having an inwardly projecting claw or jaw 38, the inner face of which is beveled inwardly and rearward and at the rear of this beveled portion, this jaw extends outward to the body of the latch. Each latch is pivoted, as at 39. The springs 40 act to force the headed end of the latch inward. These latches, as shown in Figure 6, project slightly beyond the forward end of the breech block. The forward end of the breech block has a vertically 40 extending slot 41 shown best in Figures 6 and 7, this slot being undercut so as to provide the two opposed ribs 42. The confronting beveled faces of the opposed latches project inward slightly beyond these ribs 42, as shown in Figure 6. The bore 25 at the forward portion of the breech block 50 is reduced in width and intersects a vertical slot 43 in the breech block, this slot opening into the slot 44, as shown in Figure 7. The forward portion of this bore is extended downward so as to form a longitudinally extending slot 45 upon the under side of the breech block, as shown in Figure 6. The under face of the breech block is formed with two longitudinally extending ribs 46 shown in Figure 8, and projecting downward from one of these 55 ribs is the lug 47, and projecting downward from the other of these ribs is a lug 48, this lug 48 being disposed slightly rearward of the lug 47. The rear portion of the breech housing, as shown in Figure 7^a is provided with longitudinally extending ribs 49 which engage the grooves 36, and the side wall of the breech housing is longitudinally slotted at 48 to accommodate the outwardly projecting handle or finger piece 32. Thus, the breech block may be retracted against 60 the action of the springs 33. When the breech block is released, the springs 33 will force the breech block up to the position shown in Figure 1, it being understood, however, that the hammer is, under these circumstances, retracted.

75 Mounted upon the bottom of the breech hous-

ing, as shown in Figure 8, and immediately beneath the breech block is a block 49, this block being supported immediately in advance of the hammer 14. The block is longitudinally slotted upon its upper face and is held in place by a 5 screw 50. Disposed within the slot 51 is a cartridge lifter 52 shown in side elevation in Figure 3, this lifter being pivoted upon a pin 53. This lifter, as shown in Figure 3, is provided at its forward upper corner with the forwardly projecting slightly curved nose or extension 54. The rear end of this lifter is notched at 55, and is provided with a cam 56 shown in dotted lines in Figure 3, and shown in full lines in Figure 5, which is adapted to be engaged by the lug 46, 15 as the breech block is retracted. As the breech block is retracted, this lug 46 rides up on the cam 56, depresses the rear end of the lifter 52, and lifts the finger 54 from the position shown in Figure 2 to the position shown in Figure 3, 20 thus, as will be more fully evident hereafter, lifting the cartridge up from the position shown in Figure 2 to that shown in Figure 3.

The fore-stock 11, as shown best in Figures 1 and 1^a, is formed to provide a longitudinally 25 extending chamber 57 within which is disposed a longitudinally extending magazine designated 58 as a whole, shown in elevation in Figure 9 and in partial elevation in Figures 10 and 11, and in section in Figure 13. This magazine is 30 U-shaped in cross section, as shown in Figure 12, and the forward end is curved upward and forward and notched at 59. One wall 60 of the magazine extends above the opposite wall 61 and attached to the wall 60 by screws 62 is a plate 35 63 having an inwardly turned flange 64, this flange being spaced from the upper end of the side wall 60. The space between the flange 64 and the upper edge of the adjacent side wall 60 forms in effect a relatively wide longitudinal 40 groove within which the rim of each cartridge is received, this groove being considerably wider than the thickness of the rim in order to permit the cartridges to be disposed in an inclined position with the lower or bullet end of the cartridge 45 extending downward and rearward, as shown in Figure 1, without any chance of the cartridges falling over, the cartridges being held in this inclined position as shown in Figure 1, by a follower 65 to be later described. The wall 61, as shown in dotted lines in Figure 9 and in full lines in Figures 4 and 4^a, is provided with a series 50 of outwardly projecting elongated lugs or ribs 66, 68 and 67, and with studs 69 for the attachment of springs and with an outwardly projecting lug 69 adjacent the rear end of the side wall 61 of the magazine. Reciprocating on this side wall 61 is a flat bar 70 provided with a plurality of longitudinally extending slots 71 longer and wider than the lugs 65, 66 and 67, shown clearly in 55 Figure 4^a, thus permitting this flat rod or bar 70 to reciprocate and also permitting an upward movement of the bar. The bar is drawn downward in the position shown in Figures 4 and 4^a by the springs 72 and 73 attached at their lower 60 ends to the studs 69 and at their upper ends into hooks 74 formed at the forward ends of cut-out portions 75, these recesses 75 being cut upward from the lower edge of the bar. The rear end of this bar is less in width than the forward end, 65 as shown in Figure 4, and the lower edge of this rear portion 76 rides upon the stud 69. The middle of this rear portion 76 of the reciprocatable bar 70 is cut away at 77 to receive the upper end 70 of an operating lever 78. This lever 78 has a 75

circular upper portion fitting within the circular recess 77 and the lever is pivoted at 78 upon the side wall 61 of the magazine. The lower end of this lever is provided with a fork 80 to engage with a laterally projecting pin 81 of an operating rod 82 which slides beneath the stud 69 and upon a laterally projecting stud or cross piece 83, as shown in Figure 4. This operating rod 82 at its rear end is vertically enlarged at 84, the lower edge of this enlarged rear portion being downwardly and rearwardly curved, as at 85. The upper edge of the enlarged portion 84 is formed with a notch 86 for the reception of the lug 45 on the breech block and with a pin 86^a extending upward into the breech block. Thus as the breech block is drawn rearward, the rod 82 will be drawn rearward, causing the lever 78 to turn in a counterclockwise direction shifting the rod 76 forward against the action of the springs 73. When the breech block is returned to its normal or closed position, the lug 45 will shift the rod 82 forward again and bring the rod 76 back to its original position, as shown in Figures 4 and 4^a.

The upper edge of the flat rod 76 is provided with a plurality of downwardly extending ratchet teeth 87 shown in Figures 1 and 1^a, each tooth having an upwardly and forwardly extending front face and a rear edge face which extends steeply upward and slightly rearward. It will be seen that upon the forward movement of the rod 76, that is, towards the muzzle of the gun, the teeth can ride up over the cartridges shown in Figures 1, 2 and 3, by reason of the width of the slots 71 and the elasticity of the springs 72 and 73, that is, the rear portion 76 of the rod rides upon the stud 69, but the forward end of the rod lifts so as to free the teeth from the cartridges in the magazine and ride over these cartridges and upon a reverse movement of the rod, the rod falls or moves downward to a cartridge engaging position, and upon its rearward movement moves each individual cartridge rearward, as shown in Figures 2 and 3.

Disposed within the magazine and movable therealong is a follower 88, as shown in Figure 1, the follower having its upper edge formed with two teeth 89 adapted to be engaged by two consecutive teeth 87. This follower is held in an inclined position within the magazine and its rear edge face bears against the inclined cartridges, as shown in Figure 1. The follower is provided at its lower end with a bore carrying a spring 90 which bears against one wall of the U-shaped magazine. The follower has a laterally offset finger piece 98^a which extends up through the slot or opening in the top of the magazine, as shown most clearly in Figures 12 and 16.

At the rear end of the U-shaped magazine 61 is disposed the cartridge stop designated 91, this stop being pivoted at 92 to the walls of the magazine and having a forwardly and downwardly curved nose 93. This nose is urged upward by a spring 94 bearing against the stop below the pivot 92 thereof and bearing against the end wall 95 of the magazine. The nose 54 of the lifter 52 is normally urged downward by a spring 54^a, as shown in Figures 1 and 3, so that the extremity of this nose bears against the curved upper face of the cartridge stop 91 when the breech block is in its forward position. When the breech block is in its forward position, the nose of the cartridge stop 91 is depressed, as shown in Figure 1, but when the breech block is moved toward the rear, the spring 91^a urges the nose upward

to the position shown in Figure 2 where it remains until the breech block is returned. Now when the first cartridge of the series is released by the rearmost tooth 87 of the series of teeth, the cartridge will fall down against the nose 93, as shown in Figures 2 and 3, but when the breech block moves forward the teeth 87 carried by the rod 76 are retracted, drawing the follower 88 and the whole series of cartridges rearward, and as the next succeeding cartridges of the series impinge against the cartridge, which rests upon the stop 91, the cartridge will be shifted to the nearly upright position shown in Figure 1, with its rim in line with the jaws 38 so that these jaws as they reach the rim of the cartridge, expand to embrace the rim of this first cartridge of the series. Upon a succeeding rearward movement of the breech block, the cartridge is drawn rearward over the upper faces of the nose 91 and nose 54 until it eventually reaches the position shown in Figure 2. The rim of the cartridge is then within the vertical slot 41 and the further retraction of the breech block causes the nose 54 to lift a cartridge up into the position shown in Figure 3.

The reciprocating rod 75, the lever 78 and the connecting rod 82 are housed within an outer plate 94, which is held in place by screws 65^a extending into screw holes in the lugs 65, 66 and 67, and extending into the lug 69. The rear end of this covering strip or plate 94 is cut away at 94^a upon its undermargin, thus uncovering the lower end of the lever 77 and the forward end of the rod 82. The forward end of the U-shaped magazine 58 is provided with the notches 59 and covering the forward end of the magazine is a cap 95 which is U-shaped in longitudinal section and fits immediately beneath the barrel 12, the upper wall of the cap being concavely curved to fit the barrel. Extending transversely through the side walls of the cap is a pin 96 which fits within the notches 59. The forward end of this cap is provided with a bolt 97 urged upward by a spring 98, which bolt engages the recess 99 formed in the barrel 12. The bolt 97 is attached to a slide 100 having knurled side edges whereby the bolt may be drawn downward to release the cap from the barrel and permit the cap to be removed to thus permit the magazine to be removed.

For the purpose of raising the rod 75 with its ratchet teeth 87 so as to permit cartridges and the follower to be readily placed within the magazine, I provide the lever 101 shown in Figure 4^a pivotally mounted upon the outer face of the wall 61 and having a cam-like end 102 adapted to engage against the lower edge of the rod 75 to lift this rod up, as shown in Figure 11, and thus lift the teeth 87 carried by this rod above the cartridges and above the follower, thus permitting the removal of the follower 88, then permitting the introduction of cartridges and the re-introduction of the follower which is forced into the magazine and engaged by the first two teeth of the series of teeth 87. The gun is provided with the usual safety 103 shown in Figure 1, but the safety mechanism, as it has nothing to do with my invention, need not be further described.

The breech housing 13 may be locked to the fore-stock in any suitable manner not necessary to describe, as this is common and well-known, and has no part in my invention. The upper wall of the breech housing is provided with a slot 104 whereby the cartridges may be ejected, as seen in Figure 3. As will be seen from Figure 13 plate 63 is so disposed that the flange 34 is above the 75

upper edge of the U-shaped magazine and the rims of the cartridges ride on the opposite upper edges of the walls 60 and 61 between the flange 64 and the teeth 87. Thus I have provided slots or 5 guideways to engage the rims of the loaded shells as they are placed in the front end of the magazine in a vertical position. The slots so formed are wide enough, however, to permit the cartridges to turn from an absolutely vertical position 10 to the position shown in Figures 1, 2 and 3. The operation of this mechanism will be obvious from what has gone before.

Assuming that there is no cartridge inserted in the rear end of the barrel 12, then the breech 15 block is retracted by the finger piece 32 from the position shown in Figure 1 to that shown in Figures 2 and 3. As the breech block is retracted, it forces down the hammer from the position shown 20 in Figure 1 to that shown in Figures 2 and 3. The jaws 38 have heretofore engaged the first cartridge of the series within the magazine so that upon retraction of the breech block, the first cartridge of the series is drawn rearward over the upper face of the somewhat lifted stop 91 25 and onto the upper face of the nose 54 of the lifter 52. This is the position shown in Figure 2. Upon a continued rearward movement of the breech block, the cartridge is lifted by the finger 58 to the position shown in Figure 3, the rim of the 30 cartridge moving upward within the slot 41 and being engaged by the vertical slots 41a in the side walls defining the main slot 41. If there is a spent cartridge in the front end of the breech block, it is ejected by the uplifting new cartridge, 35 as shown in Figure 3. This rearward movement of the breech block shifted the connecting rod 82 rearward and through the lever 78 shifted the cartridge feeding rod 75 forward. Upon the forward movement of the breech block, the new cartridge 40 is shifted into the barrel, the cartridge feeding rod 75 is shifted rearward by the connecting rod 82, the lifter 52 is forced downward by its spring and the stop 92 is shifted to the position shown in Figure 1 by the under face of 45 the breech block. The rearward movement of the cartridges within the magazine caused by the rearward movement of the feeding rod 75 causes the cartridge which is resting against the nose 93 of the stop 91 to be shifted to a nearly upright 50 position where it will be engaged by the jaws 38 as the breech block moves to its forwardly projected position. Each time that the gun is fired, the breech block is pulled rearward, thus cocking the hammer, inserting a new cartridge in place, and upon the release of this breech block, moves 55 forward inserting the cartridge into the barrel. As it moves forward, the plunger 30 is urged forward by the spring 31 and forces the cartridge home within the barrel, then upon the retraction 60 of the trigger 18, the hammer is released, as before described, and strikes the rear end of the firing pin 24 and projects this firing pin forward against the rim of the cartridge to detonate it. Immediately upon the detonation of the cartridge, the firing pin is retracted by the spring 31 so as to permit the ejection of the spent shell. The spring 90 in the follower 88 frictionally 65 engages the side wall of the magazine and thus acts to hold the follower tight up against the cartridges at all times so as to keep the cartridges in proper position so that they will work freely.

It will be seen from Figures 4 and 10 that when the breech block is retracted, it will pull the lever 73 to a position where the lever 78 extends 70 downward and rearward with its fork 80 extend-

ing downward and rearward, and under these circumstances, the magazine may be withdrawn with the lever in the position shown in Figure 10, which figure shows the magazine as being partially withdrawn and the lever just out of its engagement with the pin 81 on the rear end of the connecting rod 82. It is to be understood that when the magazine is returned to position within the fore-stock that the lever must be turned to the position shown in Figure 10 so that as the 10 magazine is moved into the forestock, the forked end of the lever will engage the pin 81, then as the magazine is shifted rearward, the lever will be brought to the position shown in Figure 4.

It will be obvious that my mechanism may be 15 modified to suit any caliber or model of rifle, shot gun, or other light arm and to suit any caliber of barrel.

What is claimed is:—

1. A magazine gun having a barrel, a fore- 20 stock, a manually retractible breech block and a firing pin therein; a magazine extending through the forestock in the same vertical plane as and parallel with the barrel, means for supporting a series of cartridges in the magazine with the 25 caps of the cartridges upward, a follower in the magazine, a cartridge feeding member partially embracing the magazine and reciprocatable with relation thereto and having ratchet teeth engaging the follower, means connected to and operated by the breech block acting to shift the feeding member one step forward towards the muzzle upon a rearward movement of the breech block and shift the feeding member rearward one step as the block is closed, means on the forward end of the breech block to engage the rear- 30 most cartridge of the series and draw it rearward as the breech block is retracted, a cartridge lifter disposed just below the breech block and operated by the retraction of the breech block 35 to lift the cartridge into position in front of the firing pin and in register with the barrel.

2. A magazine gun having a barrel, a forestock, a reciprocatable, manually retractible breech block and a firing pin therein; a magazine extending through the fore-stock and removable from the forward end thereof and disposed in the same vertical plane as and parallel to the barrel, means for supporting a series of cartridges in the magazine with the caps upward, a follower in the magazine removable through the forward end thereof, a reciprocatable cartridge feeding member mounted upon the magazine and having ratchet teeth engaging the follower, means connected to and operated by the breech block acting to shift the feeding member forward towards the muzzle upon a rearward movement of the breech block and to shift the feeding member rearward one step as the block is closed, means on the forward end of the breech block for gripping 50 the shell of the rearmost cartridge of the series upon a forward movement of the breech block, said gripping means drawing the cartridge rearward as the breech block is retracted, a stop over which the cartridge is drawn rearward and acting to elevate the cartridge to a horizontal position, a cartridge lifter just behind said stock, said cartridge lifter being operatively connected to the breech block and operated thereby to lift the cartridge into a position in front of the firing 55 pin and in register with the barrel.

3. In a magazine gun having a barrel, a fore- 60 stock, a manually retractible breech block and a firing pin therein; a magazine extending through the forestock in the same vertical plane as and 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 9665 9

parallel to the barrel, said magazine being removable from the forward end of the barrel, means for supporting a series of cartridges in the magazine with the caps upward, a follower 5 in the magazine having a toothed upper end, a reciprocating cartridge feeding member partially embracing the magazine and having ratchet teeth engaging the toothed upper end of the follower and acting upon a rearward movement 10 of said member to move the follower rearward and upon a forward movement of the member to travel over the teeth on the follower, means connected to and operated by the breech block acting to shift the feeding member one step forward 15 towards the muzzle of the gun upon a rearward movement of the breech block and to shift it rearward one step as the block is closed, resiliently urged jaws on the forward end of the breech block adapted to engage the cap of the 20 rearmost cartridge in the magazine and draw it rearward, a stop disposed just rearward of the magazine and having a rearwardly and upwardly extending upper edge face and over which the cartridge is drawn whereby to lift the cartridge 25 to a horizontal position, a pivoted cartridge lifter disposed just behind the stop and operated by the retraction of the breech block to lift the cartridge into a position in front of the firing pin and in register with the barrel whereby upon 30 a forward movement of the breech block the cartridge is forced into the barrel.

4. In a magazine gun having a barrel, a fore-stock, a manually retractible breech block and a firing pin therein; a magazine extending 35 through the fore-stock and approximately U-shaped in cross section, the magazine being open along its upper edge, means for supporting a series of cartridges in the magazine with the caps upward, a follower in the magazine having its 40 upper edge toothed, a reciprocating cartridge feeding member slidably mounted upon the side wall of the magazine and having a portion extending over the opening in the upper wall of the magazine, this portion being toothed and having toothed engagement with the follower to cause 45 a rearward movement of the follower upon a rearward movement of the cartridge feeding member, a forward movement of the cartridge feeding member causing its teeth to ride over the teeth on the breech block, and means operatively connected to the breech block and operated thereby to cause reciprocation of said cartridge feeding member as the breech block is retracted and projected.

55 5. In a magazine gun having a barrel, a fore-stock, a manually retractible breech block and a firing pin therein; a magazine extending longitudinally through the fore-stock and removable from the forward end thereof, a cap detachably 60 engaging the forward end of the magazine and closing it and having means whereby it may be locked in place at the forward end of the fore-stock, the magazine being U-shaped in cross section and open along its upper edge, a cartridge feeding member slidably mounted upon one side wall of the magazine, means for limiting the sliding movement of the member, springs urging the member rearward and restraining upward movement of the member relative to the magazine, 65 manually operable means for raising the movable member relative to the magazine to permit the insertion of cartridges therein, the cartridge feeding member having a flange extending over the upper opening in the magazine, the flange being ratchet-toothed on its underface, a

follower disposable within the magazine and having its upper end formed with ratchet teeth coacting with the ratchet teeth on said member, a lever pivoted on the side wall of the magazine and engaging at its upper end with the cartridge feeding member, and a connecting rod between the lever and the breech block whereby to oscillate the lever upon a reciprocation of the breech block, said lever and connecting rod being so constructed and arranged that when the breech 10 block is retracted the magazine may be withdrawn from the fore-stock and the lever and connecting rod will slide out of engagement with each other.

6. In a gun of the character described having 15 a frame, a barrel and a breech block, spring urging the breech block forward to a position against the rear end of the barrel, a hammer disposed rearward of the breech block, hammer releasing means, a firing pin mounted in the breech block 20 in alinement with the barrel, the underface of the firing pin being cut away, a plunger mounted within the breech block immediately beneath the cut-away portion of the firing pin and a spring bearing against the plunger at its forward end and against the end of the cut-away portion of the firing pin at its rear end, the spring thus urging the plunger forward and the firing pin 25 rearward but permitting the projection of the firing pin upon impact by the hammer. 30

7. In a gun, a frame, a fore-stock, a barrel, a reciprocatable breech block, a spring actuated hammer behind the breech block and trigger means for releasing the hammer, a magazine disposed within the fore-stock, the breech block having a vertical slot at its forward end undercut to engage the rim of a cartridge, a firing pin extending through the breech block in alinement with the barrel, the firing pin being cut away upon one face adjacent its forward end, a 40 plunger disposed within the breech block and having sliding engagement against the cut-away face of the firing pin, a spring disposed between the firing pin and the plunger and urging the firing pin rearward and the plunger forward, a 45 cartridge lifter pivotally mounted below the breech block, the breech block being vertically slotted to accommodate the cartridge lifter and permit it to turn, means on the breech block for engaging the rearmost cartridge in the magazine 50 whereby as the breech block is retracted, the cartridge will be drawn rearward into engagement with the upper face of the lifter, and means on the breech block engaging the lifter and tilting it to cause the cartridge to lift into position in 55 said vertical groove immediately in front of the plunger and in alinement with the barrel.

8. In a magazine gun having a barrel, a fore-stock, a manually retractible breech block and a firing pin therein; a magazine extending 60 through the fore-stock and removable from the forward end of the fore-stock, a cap detachably engaging the forward end of the magazine, means for locking the cap to the barrel of the gun when the magazine is in 65 place, said magazine being U-shaped in cross-section and open along its upper edge, means in the magazine for supporting cartridges with their caps disposed upward, a follower in the magazine having means for frictionally engaging the walls 70 thereof, the follower having ratchet teeth upon its upper end, a cartridge feeding member slidably mounted upon one wall of the magazine and having a flange extending over the upper opening of the magazine, the flange having ratchet teeth 75

engaging the ratchet teeth on the follower, the teeth having inclined forward faces, springs urging the feeding member rearward and downward, a lever pivotally mounted upon the magazine adjacent its rear end, the upper end of the lever operatively engaging the feeding member to reciprocate it, the lower end of the lever being slotted, a lug extending downward from the breech block, a slidably mounted connecting rod having one end formed with a pin engaging in the slot of said lever, the rear end having a recess to receive said lug on the breech block, springs urging the breech block forward, and manually operable means for retracting the breech block.

9. In a magazine gun having a barrel, a fore-stock, a manually retractible breech block and a firing pin therein; a magazine extending through the fore-stock and removable from the forward end of the fore-stock, a cap detachably engaging the forward end of the magazine, means for locking the cap to the barrel of the gun when the magazine is in place, said magazine being U-shaped in cross section and open along its upper edge, means in the magazine for supporting cartridges with their caps disposed upward, a follower in the magazine having means for frictionally engaging the walls thereof, the follower having ratchet teeth upon its upper end, a cartridge feeding member slidably mounted upon one wall of the magazine and having a flange extending over the upper opening of the magazine, the flange having ratchet teeth engaging the ratchet teeth on the follower, the teeth having inclined forward faces, springs urging the feeding member rearward and downward, a lever pivotally mounted upon the magazine adjacent its rear end, the upper end of the lever operatively engaging the feeding member to reciprocate it, the lower end of the lever being slotted, a lug extending downward from the breech block, a slidably mounted connecting rod having one end formed with a pin engaging in the slot of said lever, the rear end having a recess to receive said lug on the breech block, springs urging the breech block forward, manually operable means for retracting the breech block, a pivoted stock mounted below the forward end of the breech block and having a downwardly and forwardly curved nose, pivoted cartridge engaging latches mounted upon the breech block and having gripping jaws at their forward ends adapted to engage over the cap of the rearmost cartridge upon a forward movement of the breech block and draw said cartridge rearward over the upper face of the stock upon a rearward movement of the breech block, and a lifter mounted rearward of the stock and having a forwardly extending curved nose normally resting upon the upper face of the stock, and means acting upon a retraction of the breech block to tilt said lifter to cause its nose to lift a cartridge into a position in front of the firing pin and in alinement with the barrel.

10. In a magazine gun having a fore-stock and a reciprocatable breech block, a U-shaped cartridge magazine extending longitudinally within the fore-stock and removable bodily from the forward end thereof, one wall thereof having a longitudinally extending groove with which the rims of inverted cartridges engage and by which they are supported in a depending position, a cartridge feeding element having a longitudinally extending portion disposed over the longitudinal opening of the magazine and having a series of rearwardly facing ratchet notches adapted to en-

gage and support the rim ends of a series of upwardly and rearwardly extending cartridges disposed in said magazine, each notch being adapted to engage and support the butt end of a single cartridge, and means for forwardly shifting said feeding element upon a rearward movement of the breech block to permit the teeth to ride over the cartridges and shifting the feeding element upon a forward movement of the breech block rearward to cause a one-step movement of the feeding element toward the breech block.

11. In a magazine gun having a fore-stock and a reciprocatable breech block, a U-shaped cartridge magazine extending longitudinally within the fore-stock and removable bodily from the forward end thereof, one wall of the element having a longitudinally extending groove in which the rim ends of inverted cartridges engage and by which they are supported in a depending position, a cartridge feeding element having a longitudinal portion extending over the opening of the magazine and nearly its entire length and having a series of rearwardly facing ratchet notches on its inner face, each notch being adapted to engage and support the rim end of a single cartridge, the cartridges being thus disposed in an upwardly and rearwardly extending position, and means positively engaging the feeding element with the breech block, said means being constructed and arranged to reciprocate the feeding element as the breech block is reciprocated.

12. In a magazine gun having a fore-stock and a reciprocatable breech block, a U-shaped magazine extending longitudinally within the fore-stock and removable bodily from the forward end thereof, one wall of the magazine having a longitudinally extending groove in which the rim ends of inverted cartridges engage and by which they are supported in a depending position, a cartridge feeding element having a longitudinal portion extending over the opening of the magazine and extending nearly to the forward end thereof, the inner face of the feeding element having a series of rearwardly facing ratchet notches, each notch being adapted to engage and support the rim end of a single cartridge, a lever pivoted on the side of the magazine and having its upper end pivotally engaging the feeding element, and a connecting element between said lever and the breech block whereby as the breech block is retracted, the feeding element will be shifted forward and ride over the cartridges in the magazine and upon a forward movement of the breech block, the feeding element will be retracted to force the series of cartridges rearward.

13. In a gun having a barrel, a reciprocatable breech block and a hollow fore-stock, a cartridge magazine U-shaped in cross section disposed within but removable bodily from the forward end of the fore-stock, one wall of the magazine having a longitudinally extending groove with which the rims of inverted cartridges engage and by which they are supported in a depending position, a cartridge feeding element slidably mounted upon the magazine and having a longitudinally extending portion extending over the opening of the magazine and approximately co-extensive therewith and having a series of rearwardly facing ratchet notches, each notch being adapted to engage and support the rim end of a single cartridge, a lever mounted upon the magazine and pivotally engaged at its upper end with the feeding element, said lever at its lower end being forked, and a connecting rod opera-

tively connected with the breech block to be reciprocated thereby and having a pin at its forward end engaging in the fork of said lever to thus permit the retraction of the magazine and upon such retraction a disengagement between the lever and the pin of said connecting rod.

14. In a magazine gun, a barrel, a fore-stock, a manually retractible breech block, the breech block having opposed inwardly extending flanges at its forward end defining opposed grooves to engage with the rim end of a cartridge, means urging the breech block forward against the barrel, a magazine disposed within the fore-stock and open at its rear end into the breech of the gun below the breech block and held from rearward movement with the breech block, a cartridge lifter pivotally mounted in the breech below the forward end of the breech block, means positively engaging the breech block with the cartridge lifter to cause an upward movement of the lifter upon a retraction of the breech block, the breech casing behind the barrel having a shell ejecting opening in its upper wall and in vertical alignment with the forward end of the breech block when the latter is retracted whereby a cartridge moving upward in said guides under the action of the lifter will eject the spent cartridge through said opening and longitudinally reciprocating means operating within the magazine and positively connected to and operated by the breech block constructed and arranged to shift the cartridges one by one onto the cartridge lifter as the breech block is reciprocated.

15. In a gun, a magazine, means in the upper portion of the magazine for engaging the rim ends and for supporting cartridges in the magazine with their rim ends upward, and their tip ends trailing forwardly and downwardly against the bottom wall of the magazine, feeding means constructed and arranged to engage the upper end of each cartridge and feed the cartridges step by step through the magazine, and a follower in the magazine bearing against the rearmost cartridge thereof, the follower having a cartridge-facing edge-face inclined downward and away from the direction in which the cartridges are

being fed, said feeding means engaging the upper end of the follower.

16. In a gun, a magazine, means for supporting cartridges in the magazine with the rim ends of the cartridges upward, a longitudinally extending cartridge feeding rod disposed within the upper end of the magazine and having ratchet teeth facing downward and away from the direction in which the cartridges are to be fed, a follower in the magazine adapted to bear against the rearmost cartridge of the series, the follower having ratchet teeth with which the ratchet teeth on the feeding rod engage, and means for reciprocating the feeding rod to cause a step by step movement of the series of cartridges through the magazine.

17. In a gun, a magazine approximately U-shaped in cross-section, one wall thereof having a relatively wide groove adjacent the upper end of the wall to receive the rim of an inverted cartridge, a cartridge feeding member having ratchet teeth on its underface, the teeth extending down through the top of the magazine and engaging the rim end of each cartridge, and means for reciprocating the feeding member to cause a step by step advancement of the cartridges through the magazine.

18. In a gun or magazine approximately U-shaped in cross-section, one wall thereof having a relatively wide groove adjacent the upper end of the wall to receive the rim of an inverted cartridge, a cartridge feeding member having ratchet teeth on its underface extending down through the top of the magazine and engaging against the rim end of each cartridge, a follower engaging against the last cartridge of the series in the magazine and having its upper end formed with ratchet teeth for engagement by the ratchet teeth of the feeding member, the follower having a finger-piece extending out through the upper open end of the magazine whereby the follower may be manually shifted in position against the cartridges or out of such position, and means for reciprocating the feeding member to cause the step by step movement of all the cartridges towards the discharge end of the magazine.

ROBERT SCHULTZ.
